UNITED STATES PATENT OFFICE.

ELMER E. CARPENTER, OF WORCESTER, MASSACHUSETTS.

TRACK-SANDING MACHINE.

SPECIFICATION forming part of Letters Patent No. 663,215, dated December 4, 1900.

Application filed May 25, 1900. Serial No. 17,912. (No model.)

To all whom it may concern:

Be it known that I, ELMER E. CARPENTER, a citizen of the United States, residing at Worcester, in the county of Worcester and 5 State of Massachusetts, have invented a new and useful Track-Sanding Machine, of which the following is a specification.

My invention relates to a track-sanding device which has been especially designed for 10 use on electric cars; and one object of my invention is to provide a simple, inexpensive, and efficient track-sanding device having the operative parts thereof located so that dust and ice will not be allowed to collect upon 15 the same and so that the sanding device will always be ready for use.

A further object of this invention is to deliver the sand directly in front of the wheels, especially when going around curves, at which 20 times the car-body occupies a different position with respect to its trucks than when running on a straight section of track.

To these ends this invention consists of the track-sanding device and the combinations 25 of parts therein, as hereinafter described, and more particularly pointed out in the claims at the end of this specification.

In the accompanying drawings, Figure 1 is a fragmentary view illustrating part of an 30 electric car provided with a track-sanding device constructed according to this invention. Fig. 2 is a perspective view of the upper part of the valve-casing. Fig. 3 is a perspective view illustrating the valve and the 35 connections for operating the same, and Fig. 4 is a perspective view illustrating the lower part of the two-part valve-casing.

In order to provide a reliable track-sanding device which may be always depended 40 upon to remain in operative condition, I have found it essential that the sand should be kept warm and dry and that the working parts of the track-sanding device should be located in such a way that dust and ice can- 45 not accumulate thereon.

With these ends in view a track-sanding device constructed according to my invention comprises a sand-box, a pipe for delivering sand onto the rail, a two-part valve-casing, 50 and a valve mounted to move transversely between the parts which constitute the valve-casing. The sand-box is preferably of a trun-

cated or tapering form and may be located in any convenient position inside the car, preferably under one of the seats. A pipe extends down from the sand-box, and bolted or otherwise secured on the under side of the car-floor is a two-part valve-casing. The parts of the two-part valve-casing may be bolted together by means of flanges, and as 55 the valve-casing may thus have a comparatively slight depth it will stand high enough above the track on which the car runs so that dust or ice will not be liable to collect thereon, and, if desired, it may even be boxed 60 in or inclosed.

The larger number of electric cars which are now employed have the car-bodies mounted on trucks, two trucks having four wheels each being usually provided for each car. When 70 one of the larger electric cars passes around a curve, the trucks do not stay in line with the car-body, and if it is attempted to deliver sand direct from a sanding device mounted rigidly in the car-body the sand will be delivered 75 either inside or outside of the track when the car is on a curve. To overcome this objection, I propose to employ a flexible pipe having its upper end clamped on to the two-part valve-casing, while its lower end is connected 80 to and moves with the truck, so as to deliver sand immediately in front of the car-wheel under all circumstances.

Referring to the drawings and in detail, the sand-box 10 of a track-sanding device, as 85 herein illustrated, is of a one-side truncated or tapering form, said sand-box being preferably made of sheet metal and having its upper edges secured to the framework of one of the car-seats, the cushion 11 of said car-seat forming the cover of the sand-box. Extending from the sand-box 10 through the floor of the car is a short pipe 12, which connects to the upper section 13 of a two-part valve-casing. The construction of the two-part valve-casing is most clearly illustrated 95 in Figs. 2 to 4. As shown, the upper section 13 of the two-part valve-casing has an upper or supporting flange for bolting or securing the valve-casing to the under side of 90 the car-floor and is also provided with a lower flange 15, having an extending arm 16, forming a truck or support for the movable valve which fits between the parts constituting the 100

two-part valve-casing. The flange 15 is chambered or cut away, as at 18, to receive the lever carrying the valve. The valve, which is mounted between the parts of the two-part 5 valve-casing, preferably comprises a sheet-metal plate 22, carried by an arm or lever 23. The arm or lever 23 is normally drawn back by a spring 24 to hold the valve in its closed position. The arm or lever 23 is also connected by a cord or wire 25 to a bell-crank 26, which may be operated by a footpiece 27, located at the front of the car in position to be controlled by the motorman. The lower part 10 of the two-part valve-casing has an upper 15 flange 19 and an extending arm 20, corresponding with the arm 16 of the upper section of the valve-casing. The flange 19 of the lower part of the two-part valve-casing is recessed or chambered out, as at 21, to receive 20 the valve-plate 22. By means of this construction when the two parts of the valve-casing are bolted together the lever carrying the valve-plate may be pivoted on one of the bolts, so that the valve-plate may swing or 25 move transversely in the chamber or recess 21 of the lower part of the two-part valve-casing. When the valve is thrown wide open—for example, by actuating the footpiece 27—the arms 16 and 20 will form supports for preventing its displacement or injury.

By employing a valve mechanism of this character the operative parts of a track-sanding device constructed according to my invention may be located directly under the floor 35 of the car and some distance above the track, so that they can be conveniently housed or boxed in—for example, by a housing or box • B—if desired.

A pipe 29 extends down from the lower 40 part of the two-part valve-casing, and clamped onto the pipe 29 is a flexible pipe or hose 30. The lower end of the hose 30 extends through a clip or ring 31, carried by the guard-frame F of the truck, and I prefer to arrange the 45 parts in this manner in order to insure delivering sand immediately in front of the wheel W even when the car is going around a curve.

I am aware that changes may be made in

the proportions and arrangement of parts in a track-sanding device constructed according 50 to my invention by those who are skilled in the art without departing from the scope of my invention as expressed in the claims.

I do not wish, therefore, to be limited to the details herein shown and described; but 55

What I do claim, and desire to secure by Letters Patent of the United States, is—

1. In a track-sanding device, the combination of a sand-box, a pipe extending from said sand-box through the floor of a car, a two-part valve-casing supported on the under side of the floor of the car, a pivoted lever carrying a valve-plate, and connections for operating the pivoted lever from the car-platform, the parts of the two-part valve-casing being 6; secured together by flanges, the flange of one part being recessed to receive the pivoted lever, the flange of the other part being recessed to receive the valve-plate, and said flanges having corresponding arms for supporting the valve-plate when open, substantially as described.

2. In a track-sanding device, the combination of a tapering or truncated sand-box 10 located under a car-seat so that the cushion 75 thereof forms the cover of the sand-box, a pipe 12 extending from the sand-box through the floor of the car, a two-part valve-casing secured on the under side of the car-floor, a pivoted lever 23 carrying a valve-plate 22, 80 connections for operating the pivoted lever, and a flexible pipe or hose having its lower end movable with the car-truck, the upper section of said two-part valve-casing being recessed or chambered out, as at 18, to receive 85 the pivoted lever, and the lower part of the two-part valve-casing being recessed or chambered, as at 21, to receive the valve-plate, substantially as described.

In testimony whereof I have hereunto set 90 my hand in the presence of two subscribing witnesses.

ELMER E. CARPENTER.
